UNITED STATES PATENT OFFICE.

MIROSLAV VISKOCHIL, OF SHETLAND, MICHIGAN.

CUTTER-BAR.

SPECIFICATION forming part of Letters Patent No. 628,873, dated July 11, 1899.

Application filed April 10, 1899. Serial No. 712,449. (No model.)

To all whom it may concern:

Be it known that I, MIROSLAV VISKOCHIL, a citizen of the United States, residing at Shetland, in the county of Leelanau and State of Michigan, have invented new and useful Improvements in Cutter-Bars, of which the following is a specification.

My invention relates to improvements in cutter-bars for mowing and reaping machines, and pertains to a cutter-bar provided with a clamping device for clamping the blades of the cutter-bar by a single movement thereof and also for releasing the cutter-blades, all of which will be fully described hereinafter and particularly pointed out in the claims.

The object of my invention is to provide a cutter-bar for reaping and mowing machines in which there is provided a bar or member carrying headed clamping-bolts, which are adapted to engage the edges of the blades of the cutter-bar, and a cam member for forcing the clamping-bolt bar or member outward, and thus clamping the blades, and by means of which one or more of the blades can be detached when broken or injured and others quickly substituted therefor.

In the accompanying drawings, Figure 1 is a perspective view of a cutter-bar embodying my invention. Fig. 2 is a longitudinal vertical section. Fig. 3 is a perspective view of the detached clamping-bolt bar and the headed bolts carried thereby. Fig. 4 is a view of the detached cam-bar. Fig. 5 is an under plan view of a portion of a bar, showing the cutter-blades.

Referring now to the drawings, A indicates the cutter-bar, which may be of any desired form or size, and B the cutter-blades. These cutter-blades instead of being riveted to the cutter, as is usually the case, are made quickly detachable and attachable by means of the headed bolts C. These bolts C pass through the cutter-bar and their enlarged ends a engage adjacent recesses b, made in the opposite edges of the cutter-blades, and when drawn outward the heads of these bolts serve to clamp and firmly hold the cutter-blades, as will be readily understood.

A rod or bar D extends longitudinal the cutter-bar A and is united to the outer and upper ends of the bolts C. The under side of the bar D is provided with the cam-surfaces

c, and situated between the bar D and the cutter-bar A is a longitudinally-movable cam-bar G. This bar G is provided with a plurality of cam-surfaces d, adapted to coact with the surfaces c of the bar D, and the bar G is provided with elongated slots e, through which the bolts C freely pass. These slots e permit the bar G to be reciprocated for causing its cam-surfaces to engage the cam-surfaces of the bar D for locking the blades and to carry the said cams out of engagement for releasing the blades.

When it is desired to detach one or more of the cutter-blades B, the cam-bar G is moved endwise to have its cam-surfaces between the cam-surfaces of the bar D. In this position the clamping-bolts are permitted to move inward or downward and the cutter-blades to be readily and quickly removed for the purpose of being repaired or for the purpose of substituting another in its place. When the repaired or new cutter blade or blades are placed in position, the endwise movement of the bar G simultaneously clamps all of the cutter-blades through the medium of the headed bolts C.

The bar G will be held in its locked position by means of a set-screw H, though it may be held in its locked position in any other desired manner without departing from the spirit and scope of my invention.

This invention is especially useful in that when a cutter-blade becomes injured in the field the operator can in a few moments detach the injured blade and put in its place a new blade, thus saving a great deal of time, and consequently economizing the mowing operation as compared with the old cutter-bar, in which the blades are held in position by rivets. When the cutter-blades are held by rivets in the usual way, considerable time is lost in the backing out of the rivets and the placing of new ones therein.

Having thus described my invention, what I claim, and desire to secure by Letters Patent, is—

1. An improved cutting device comprising a cutter-bar, cutter-blades carried thereby, headed bolts passing through the cutter-bar and engaging the said blades, a rod connecting the headed bolts, and an endwise-moving cam-bar adapted to force the bar carrying the

bolts outward for clamping the blades, substantially as described.

2. An improved cutting device comprising a cutter-bar, cutter-blades carried thereby, bolts passing through the cutter-bar and having heads engaging the said blades, and an endwise-moving cam-bar adapted to force the headed bolts outward for clamping the cutter-blades, substantially as described.

10 3. An improved cutting device comprising a bar adapted to carry cutter-blades, cutter-blades resting thereagainst and having bolt passage-ways, headed bolts passing through the bar and adapted to engage the walls of the said passage-ways, the opposite ends of the bolts extending beyond the cutter-bar, and an endwise-moving cam-rod between the extended ends of the bolts and the cutter-bar and adapted by endwise movement to clamp 20 and release the said bolts, substantially as described.

4. An improved cutting device comprising a cutter-bar, cutter-blades carried thereby and having bolt passage-ways, bolts passing through the cutter-bar and having enlarged heads adapted to engage the walls of the passage-ways of the cutter-blades, a rod uniting the opposite ends of all of said bolts and hav-

ing cam-surfaces on its inner side, an endwise-moving rod situated between the bolt-uniting bar and the cutter-bar, said endwise-moving rod or bar having cam-surfaces adapted to engage the cam-surfaces of the bolt-uniting bar for the purpose of clamping and releasing the heads of said bolts against the cutter-blades, substantially as described.

5. An improved cutting device comprising a cutter-bar, cutter-blades adapted to be carried thereby and having bolt passage-ways, bolts passing through the cutter-bar and having heads engaging the walls of said passage-ways, a bar uniting the opposite ends of said bolts and having inwardly-extending cam-surfaces, a cam-bar situated between the bolt-uniting bar and the cutter-bar, said cam-bar having elongated openings through which the bolts pass and also cams adapted to engage the cams of the bolt-uniting bar, substantially as and for the purpose described.

In testimony whereof I have hereunto set 50 my hand in the presence of two subscribing witnesses.

MIROSLAV VISKOCHIL.
